UNITED STATES PATENT OFFICE.

ANSON C. ALEXANDER, OF PENACOOK, NEW HAMPSHIRE.

DESIGN FOR A BOTTLE.

SPECIFICATION forming part of Design No. 24,400, dated June 18, 1895.

Application filed October 22, 1894. Serial No. 526,649. Term of patent 7 years.

To all whom it may concern:

Be it known that I, ANSON C. ALEXANDER, a citizen of the United States, residing at Penacook, in the county of Merrimac and State 5 of New Hampshire, have invented a certain new and original Design for Bottles; and I do hereby declare the following to be a full, clear, and exact description of the invention, such as will enable others skilled in the art 10 to which it appertains to make and use the same.

My design relates to bottles which are open at both ends, and consists of the peculiar contour of the bottle and its neck, and of the 15 particular ornamentation consisting of bands and scrolls which will be fully set forth in the following specification and clearly illustrated in the accompanying drawing forming a part of the same.

20 The bottle A, is globular, and has a circular neck B, which is quite small in diameter in relation to the bottle, and as long or slightly longer than is the diameter of said bottle, and near its outer end said neck is re-

duced annularly as at C, which reduced portion terminates in a flange D; said neck having a cork E.

Diametrically opposite to the neck is formed an opening F, in the bottle, around which is formed a flange G, and this as well as the 30 flange D, is artistically curved as shown, the opening F being fitted with a cork or other stopple H.

The ornamentation of the bottle consists of a scroll in which lines are made to cross each 35 other at angles as at I, and in the annular bands placed above and below said scroll as shown.

Having described my design, what I claim is—

The design for a bottle substantially as 40 herein shown and described.

In testimony whereof I affix my signature in presence of two witnesses.

ANSON C. ALEXANDER.
